FOOTBALL PRACTICE APPARATUS WITH FORCE INDICATING MEANS

Peter Paul Janich III, 4650 Pepperwood Ave., Long Beach, Calif. 90808, and Vince J. Chaverini, 3382 Jane St., Riverside, Calif. 92506

Filed Mar. 4, 1964, Ser. No. 349,459

6 Claims. (Cl. 73—380)

The present invention relates generally to the field of athletic equipment, and more particularly to an apparatus for use in football practice to determine the blocking capabilities of a player, as well as the force a player can exert on the line of scrimmage.

In the past, various devices have been evolved and used to test a football player's skill, but in the main, such equipment has been heavy and cumbersome and met with but limited commercial success. Furthermore, such prior devices have not been capable of measuring with any degree of accuracy, the blocking capability of an individual.

A major object of the present invention is to provide a football practice apparatus that eliminates substantially all of the disadvantages found in previously available equipment of the type described, and one that can be used to test individually, either a player's blocking ability or the force he can exert at the line of scrimmage.

Another object of the invention is to furnish a football practice apparatus that is compact, can be moved to any desired location on a field or in a gymnasium, is of simple mechanical structure, and one which requires a minimum of maintenance attention.

These and other objects and advantages of the invention will become apparent from the following description of a first and a second form thereof, and from the drawings illustrating the same, in which:

FIGURE 1 is a perspective view of the football practice apparatus of the present invention;

FIGURE 2 is a front elevational view of the practice apparatus;

FIGURE 3 is an exploded perspective view of the device;

FIGURE 4 is a combined longitudinal and side elevational view of a first alternate form of the practice apparatus;

FIGURE 5 is a fragmentary vertical cross-sectional view of the apparatus, taken on the line 5—5 of FIGURE 1;

FIGURE 6 is an enlarged fragmentary vertical cross-sectional view of the device;

FIGURE 7 is an enlarged detailed view of the portion of the apparatus encircled in dotted line in FIGURE 6;

FIGURE 8 is a fragmentary transverse cross-sectional view of the apparatus, taken on the line 8—8 of FIGURE 6;

FIGURE 9 is an enlarged fragmentary perspective view of the forward upper portion of the frame for the apparatus;

FIGURE 10 is a side elevational view of a ring that is slidably mounted on the housing, shown in FIGURE 1; and

FIGURE 11 is a side elevational view of an alternate form of the apparatus.

With continuing reference to the drawings for the general arrangement of the invention, it will be seen in FIGURES 1 and 2 that an elongate blocking pad A is provided which is movably supported from a frame B. The pad A is adapted to occupy either a first position shown in solid line in FIGURE 2, or a second position shown in phantom line in the same figure wherein the major axis of the pad is horizontally positioned.

2

The pad A is supported on the forward end of a first rod C that is slidably mounted in a cylinder D, which in turn is affixed to frame B. A circular plate E is affixed in an intermediate position on rod C, and this plate is at all times situated within the confines of cylinder D. A helical spring F is also located within cylinder D, one end of which is in abutting contact with plate E. Spring F at all times resists rearward motion of pad A, rod C, and plate E relative to frame B.

10 An elongate tubular housing G is affixed to the rear end of cylinder D. Housing G supports a longitudinally extending graduated scale H at an elevated position thereabove. A ring J is slidably supported on housing G, and two laterally spaced needles K project upwardly from this ring, positioned on opposite sides of the scale H.

15 A second rod L is connected to the rear end of the first rod C. A crosspiece M extends outwardly in opposing directions from the junction of rods C and L, and is removably affixed thereto. Crosspiece M projects through two longitudinally extending, oppositely disposed slots N formed in housing G. When rods C and L and crosspiece M are moved relative to housing G, the crosspiece moves ring J on the housing. The needles K indicate on scale H the degree to which the ring J has been moved.

20 25 The degree of movement of ring J on housing G is proportional to the magnitude of force applied to pad A, or to an eye O formed on the rear end portion of second rod L.

25 30 The eye O is so formed that a bucking strap (not shown) may be affixed thereto, and this strap is affixed to a harness (not shown) which is worn by a player. While wearing the harness, a player runs in a crouched or lowered position in a direction away from frame B whereby the eye O then transfers the force of the player's run to 35 the rod L. Movement of rod L, crosspiece M, and rod C causes movement of ring J and needles K on housing G to indicate the force exerted by the player while running in such a manner.

35 40 In detail, the frame B comprises a vertical channel 10 that includes a web 12. Two flanges 14 extend rearwardly from the longitudinal edges of web 12. Two triangular gussets 16 are affixed to the lower portions of flanges 14 by bolts 18 which project through bores 20 formed in the flanges and gussets. The lower ends of gussets 16 are 45 connected by a trapezoidal crosspiece 22.

45 50 Two elongate members 24 of L-shaped transverse cross section are provided, each of which includes a vertical flange 26 and a horizontal flange 28. A number of bores 30 are formed in each flange 26, which are alignable with bores 30 formed in one of the gussets 16. Bolts 32 project through bores 30 to secure members 24 to the gussets 16 as shown in FIGURE 1.

55 60 A third elongate member 34 is provided that is of L-shaped transverse cross section, which has two gussets 36 on the ends thereof. Bolts 38 pass through aligned bores 40 formed in the rear portions of flanges 26 and the lower part of gussets 36 to removably hold the members 24 and 34 together as a unit, which in cooperation with crosspiece 22, define a base P.

65 70 Two gussets 42 in which bores 44 are formed that are alignable with bores 44 formed in the upper portions of flanges 14 are provided. Bolts 46 extend through bores 44 to hold gussets 42 and channel 10 of frame B together as a unit. Bolts 48 and 50 are formed in gussets 42 and 36 that are alignable with like numbered bores formed in two elongate reinforcing legs 51. Bolts 52 and 54 extend through bores 48 and 50 to removably connect legs 50 to gussets 42 and 36.

75 80 The cylinder D includes an elongate shell 56 that has a rearwardly disposed end piece 60 from which a tubular boss 62 projects. The forward end of shell 56 is tapped,

and receives an externally threaded plug 58 through which a bore 64 extends longitudinally. Plug 58 has threads 66 formed thereon that engage a tapped bore 68 formed in web 12, as best seen in FIGURE 3. The two reinforcing legs 51 have transversely aligned plates 70 welded or otherwise affixed thereto, as best seen in FIGURE 5. A crosspiece 72 is provided, that has an opening 74 formed therein through which boss 62 extends. The ends of crosspiece 72 are removably affixed to plates 70 by bolts 76.

A plate E is slidably movable inside shell 80, and this piston is rigidly connected to the first rod C that is slidably supported in bores 64 and 76 which extend through end piece 60 and boss 62. A resilient helical spring F is disposed within cylinder D that bears against plate E and at all times tends to retain the piston and first rod C in the position relative to cylinder D shown in FIGURE 6.

Housing G comprises an elongate tubular shell 80 that has a heaved forward end portion 82 which removably engages that part of boss 62 which projects rearwardly of crosspiece 72. Housing G is removably held on boss 62 by a number of set screws 84 which project through tapped bores (not shown) formed in end portion 82, with the inner ends of these screws frictionally gripping the exterior surface of the boss 62.

The rear end of shell 80 is closed by an end piece 88 in which a centrally disposed bore 90 is formed. The second rod L is slidably supported on bore 90, and a pin 92 provided with threads 94 extends forwardly from this rod, as may best be seen in FIGURES 6 and 7. The threads 94 engage a tapped bore 96 formed in the rear end of first rod C. Two slots N are formed in shell 80.

A central portion 98 of crosspiece M is adapted to be disposed in a space 100 formed between the adjacent end surfaces of first rod C and second rod L (FIGURES 6 and 7). When the rod L is rotated in an appropriate direction relative to rod C, the width of space 100 is decreased, whereby crosspiece M is rigidly connected to these rods due to the adjacent end surfaces of the rods being in gripping contact with portion 98. The eye O is formed as a part of the rear end of rod L, or rigidly connected thereto by conventional means.

The forward and rear portions 102 and 104 respectively, of the scale H support the scale at an elevated, longitudinally extending position above shell 80. Graduations 106 are imprinted on scale H. The ring J includes a resilient O-ring 108 that is affixed by conventional means to the interior thereof, and the internal diameter of this O-ring is such as to permit it to engage the external surface of shell 80 with a slight amount of friction when the ring is mounted on the shell, as shown in FIGURE 3. When the outwardly extending legs 110 of crosspiece M engage ring J, the ring is moved along shell 80. The needles K mounted on ring J indicate the degree of this movement on graduations 106. O-ring 108 prevents inadvertent movement of ring J on shell 80 to give a false reading.

The blocking pad A includes a first elongate steel plate 110 having a body of resilient material 112 disposed forwardly thereof. The material 112 is covered by a canvas sheet 114 that laps over the rear surface of plate 110. Lacings 116 engage the overlapping canvas portions and removably secure the resilient material 112 and canvas 114 to the first plate 110, as shown in FIGURE 1. A second steel plate 118 of smaller dimensions than first plate 110 is welded, or otherwise secured, to the rear central portion of the first plate.

A first collar 120 is rigidly affixed to the center of second plate 118 and extends rearwardly therefrom. Collar 120 is provided with a set screw 122 by which the collar is removably affixed to the forward end of first rod C, as shown in FIGURE 1. A second collar 124 is affixed to the rear surface of second plate 118, spaced a substantial distance from the first collar 120. Collar 124 is also provided with a set screw 125 which removably affixes the collar to the forward end of a guide rod 128.

Guide rod 128 may extend rearwardly through either of two openings 130 formed in web 12, which openings are spaced 90° from one another. A tubular sleeve 132 is affixed to each of the openings 130 and extends rearwardly from web 12. When guide rod 128 projects through one of the openings 130, the major axis of the blocking pad A is vertically disposed, as shown in FIGURE 2 in solid line, and when the rod 128 is in the other openings, the major axis of the pad is horizontally disposed as illustrated in phantom line in the same figure.

10 The frame F is conveniently maintained at a desired location in a playing field by attaching the same to concrete blocks 134 that are embedded in the ground. Each block 134 envelops the sides of a vertically extending 15 tapped tubular member 136, best seen in FIGURE 2, which can be threadedly engaged by bolts 138. One of the bolts 138 extends downwardly through an opening (not shown) in crosspiece 22. Two other bolts 138 extend downwardly through openings (not shown) formed in 20 horizontal webs 140 which extend between the frame members 24 and 34 at the junction thereof. Should it be desired to use the apparatus indoors, the tubular members 136 can be embedded in the floor of a gymnasium, or other fastening means provided to hold frame B at 25 a fixed position on the gym floor.

The use and operation of the practice apparatus have been described in detail hereinabove, and need not be repeated.

A first alternate form of the invention may be provided 30 by removing cylinder D from the supported position shown in FIGURE 6 and substituting the air cylinder Q shown in FIGURE 4 therefor. A piston R is slidably mounted in cylinder Q. Piston R is connected to the rear end of a rod C' that is identical to rod C, and extends 35 through a plug 58' which is identical to plug 58. Plug 58' closes the forward end of cylinder Q, and a pressure air gauge S is connected to the interior of the cylinder. Air or gas under pressure can be discharged into the interior of cylinder Q through an inlet connection T that is provided 40 with a valve U. The magnitude of the force exerted by a player on the pad A is reflected by movement of the needle 142 forming a part of the gauge S. The force required to be exerted on pad A to move the needle 142 will be proportional to the pressure to which the cylinder Q is charged.

45 A side elevational view of an alternate form of the practice apparatus of the present invention is shown in FIGURE 11. The upper portion of this alternate form of the apparatus is similar to that previously described, other than that the frame B is replaced by a rigid upright T. 50 The same numerals used in identifying the component parts of the first form of the invention are used in identifying like elements in the alternate form thereof, but a prime has been added thereto.

55 The lower end portion of upright T is slidably insertable in a vertical tubular sleeve 140 that projects downwardly through an opening 142 formed in a floor 144. The sleeve 140 is embedded in a block of concrete 146 or other anchoring means. The upper interior end of sleeve 140 is tapped and receives a bushing 148. Pairs of 60 diametrically opposed bores 150 are formed in bushing 148 which are vertically alignable with similar bores (not shown) formed in the lower portion of upright T. A bolt or pin 152 may be extended through the pairs of bolts 150 to removably support the device relative to the floor 144, as shown in FIGURE 11.

65 The alternate form of the device is used in the same manner as the form first described.

Although the present invention is fully capable of 70 achieving the objects and providing the advantages hereinbefore mentioned, it is to be understood that it is merely illustrative of the presently preferred embodiments thereof and we do not mean to be limited to the details of construction herein shown and described, other than as defined in the appended claims.

We claim:

1. A portable football practice apparatus capable of being disposed in an operative position in a vertically positioned sleeve embedded in the ground, including:
  - (a) a vertically positioned upright, the lower end portion of which is disposed in said sleeve;
  - (b) first means for preventing rotation of said upright relative to said sleeve;
  - (c) a horizontal cylindrical shell mounted on the upper end of said upright;
  - (d) a blocking pad disposed forwardly of said shell;
  - (e) a first horizontally movable rod, a forward end of which is affixed to said blocking pad and extends longitudinally through said shell;
  - (f) a plate affixed to said first rod, which plate is disposed inside said shell;
  - (g) force generating means in said shell that at all times tend to maintain said plate in a forwardly disposed position, but with said force generating means yielding to permit concurrent rearward movement of said blocking pad, first rod and plate when a player exerts a rearwardly directed force against said plate, with the magnitude of yield of said force generating means being proportional to said force exerted by said player against said pad;
  - (h) means for visually indicating said magnitude of said yield of said force generating means;
  - (i) second means for maintaining said pad in a non-rotating position relative to said upright;
  - (j) an eye to which a bucking strap can be affixed; and
  - (k) means connecting said eye to the rearward end of said first rod.

2. A football practice apparatus as defined in claim 1 wherein said force generating means comprises a helical spring in said shell, the forward end of which spring is in abutting contact with the rear surface of said plate.

3. A football practice apparatus as defined in claim 1 wherein said blocking pad includes:

- (a) a first elongate rigid plate;
- (b) a resilient body disposed forwardly of said first plate;
- (c) a pliable sheet extending over said resilient body which overlaps rear edge surfaces of said first shell for holding said body in abutting contact with said first plate;
- (d) a second rigid plate affixed to the rear central portion of said first plate;
- (e) a collar projecting rearwardly from said second plate in which a forward end portion of said first rod is disposed; and
- (f) means for removably holding said forward end portion of said first rod inside said collar.

4. A football practice apparatus as defined in claim 1 wherein said visual indicating means includes:
  - (a) a cylindrical housing in which oppositely disposed, longitudinally extending slots are formed;
  - (b) means for supporting said housing in coaxial alignment with said shell;
  - (c) a graduated elongate scale supported in a longitudinally extending elevated position above said housing;
  - (d) a ring slidably mounted on said housing;
  - (e) said eye connecting means consisting of a second rod in coaxial alignment with said first rod and affixed to the rear end thereof, which second rod is at least partially situated within said housing;
  - (f) a crosspiece in said housing that projects outwardly through said slots, with said crosspiece being removably gripped between adjacent end surfaces of said first and second rods, which crosspiece serves to move said ring rearwardly on said housing when said first and second rods are moved rearwardly by exertion of a rearward force by a player on said blocking pad; and
  - (g) at least one needle that extends upwardly from said ring to a position adjacent said scale to permit the accurate reading of the distance said ring has been moved on said housing, which reading indicates the maximum force said player has exerted on said blocking pad.

5. A football practice apparatus as defined in claim 4 which further includes means on said ring for preventing inadvertent movement of said ring on said housing.

6. A football practice apparatus as defined in claim 5 wherein said means for preventing inadvertent movement of said ring on said housing comprises a circular resilient band affixed to said ring, with said band being of such dimensions as to frictionally engage said housing.
